UNITED STATES PATENT OFFICE.

ORLANDO GARRISON, OF DAYTON, OHIO.

GEAR GRINDER.

Application filed September 4, 1923. Serial No. 660,804.

To all whom it may concern:

Be it known that I, ORLANDO GARRISON, a citizen of the United States, residing in Dayton, in the county of Montgomery and State of Ohio, have invented certain new and useful Improvements in Gear Grinders, of which the following is a specification, reference being had therein to the accompanying drawings.

10 This invention relates to improvements in gear grinders, having particular reference to the type of machine illustrated and described in Letters Patent of the United States No. 491,653, issued to me March 26, 15 1923.

The objects attained in the later improvements which constitute the subject matter of the present invention relate to the mechanism for dressing the abrasive disc, or 20 grinder wheel, by means of which the gears are ground.

In commercial practice of gear grinding both quality and quantity must be attained,—accuracy within very close limits and output on a production cost basis must be maintained. The grinder wheel is one of the determining factors of these results. The allowed limits of accuracy can be maintained only by keeping the grinder wheel properly 25 dressed, and output necessary to profitable operation can be realized only by sustained production.

Thus the objects attained in these later improvements relate to the location of the 30 wheel dresser relative to other coordinated mechanisms; to its general construction which tends to maintain accuracy of the mechanism with minimum attention given thereto; to simplicity of operation and the 35 time required for dressing operation, all of which are determining factors, more or less, which enter into commercial gear grinding.

To this end, as shown in the accompanying drawings, the dresser is located in close 40 proximity to the grinder wheel, the mechanism in all its parts is constructed to exclude grit and to minimize wear, the dressing operations are simple, of short duration and do not require skill on the part of the 45 operator.

In the drawings:

Fig. 1, is a side elevation of a gear grinder of the type herein referred to; having the improved wheel dresser applied thereto;

Fig. 2, is a detail longitudinal sectional view of the dresser;

Fig. 3, is a transverse sectional view taken on the line 3—3 of Fig. 2;

Fig. 4, is a cross sectional view taken on the line 4—4 of Fig. 2.

The gear grinder shown in Fig. 1, of the drawings serves merely to illustrate the application of the improved grinder wheel dresser to one type of machine, it being understood that the wheel dresser has general application. The main machine, therefore, as here shown, being no part of the invention except the illustrative relation it sustains thereto, will be given only a brief general description as an introductory to the detailed specification.

The supporting structure of the machine comprises a base —1, base housing —2, supported on base —1, a knee, or overhanging table —3, projecting forwardly of housing —2, and a ram —4, operable on housing —2, the grinder wheel dresser —5, as here shown being mounted on the ram.

Power is applied to the main machine by means of a belt pulley —6, and intermediate pulleys —7 and —8, connected one with the other by a belt —9, the ram being driven from pulley —8, by suitable connections inside housing —2. The grinder wheel —10, is driven by a belt pulley —11, an intermediate pulley (not shown) attached to shaft —13, upon which the grinder disc is mounted, the intermediate pulleys being connected one with the other by a belt —14. Suitable connections are also made between the driving mechanism inside housing —2, and the mechanism supported on table —3, for moving the work —15, gears to be ground rotatably and laterally relative to the grinder wheel —10, and to align the work in accurate relations therewith to receive the grinding operation.

The grinder wheel is supported on the ram by means of a forwardly extended bearing bracket —16, which is connected to the end of the ram by a dovetailed construction —17, a feed screw —18, connected to the bracket —16, by a threaded lug —19, and operable by a handle —20 serving as a means to adjust the grinder wheel vertically relative to the work, a graduated scale —21, indicating the extent of vertical adjustment thereof.

Secured to bracket —16, by means of

- screws —22, and adjusted vertically by means of jack screws —22^a, is a second overhanging bracket —23, and connected to bracket —23, by a dovetailed construction 5 —24, is a third overhanging bracket —25, a feed screw —26, supported on bracket —23, and connected to bracket —25, by a screw lug —27, and operated by a handle —28, serving as a means for adjusting bracket 10 —25, and the wheel dresser which is carried thereby, vertically relative to the grinder wheel —10, a graduated scale —29, serving to indicate the extent of vertical adjustment thereof.
- 15 Formed integrally with bracket —25, is an apertured base member —30 which extends forward of the bracket, overhanging the grinder wheel and serving as a bearing support for an apertured, rotatable member 20 —31, provided with an annular flange —32, which serves to support member —31 on base member —30. The lower portion of member —31, extends through the bearing aperture of member —30, and is threaded to 25 receive a bearing collar —33, and a bearing adjusting ring —34. Secured to flange —32, of member —31, by means of screws —35, is a band —36, which is provided with opposite notches —37, adapted to be engaged by a 30 pawl —38, pivoted on one extension —39, of member —30, and having a handle —40, for disengaging the pawl from notches —37; a handle —41 is also secured to member —31 to provide for moving the member 35 together with the wheel dresser, which is carried by it a half turn.
- Member —31 is further provided with an upwardly extended portion —42, and a downwardly extended portion —43, which 40 support the wheel dresser supporting member —44, the connection between parts —42 and —43 and housing —44, consisting of a double dovetailed construction —45, and —46, the parts being retained in proper adjustment one with the other by means of an angle block —47, secured to member —44, by a screw —48. The method of mounting the wheel dresser also provides for setting member —44, at any desired angle relative 45 to the vertical members —42, and —43, and a scale —49 secured to member —42, serving to indicate the degree of angularity and the set screw —48, to retain the parts in position.
- 50 Wheel dresser member —44, has a head portion —50, formed integrally therewith, and a channelled member —51, secured thereto in any suitable manner, the channel being covered by a plate —52, mounting of parts —51 and —52, being preferably by means of screws (not shown). Slidably operable in the channel of part —51, is the dresser tool bar —53, which is connected at its upper end as at —54, to a feed screw 55 —55, which operates axially in a threaded
- rotatable sleeve —56, the sleeve being operable rotatably by means of a handle —56^a, connected to sleeve —56 by means of a head screw —56^b. Thus upon turning of the handle 56^a, the dresser tool will be moved 70 longitudinally in the channel of member —51, into engagement with the grinder wheel. To effect a close bearing relation of bar —53, in the channel of member —51, a bearing plate —57, is inserted along one edge 75 thereof and is adjustable relative thereto by means of screws —58, set in the adjacent well of member —51. The lower end of bar —53, extends beyond member —51, and is provided with a head —59, in which carbons or 80 diamonds —60 and —61, are mounted for dressing the grinder wheel.
- Bar 53, is moved in its angular longitudinal plane by turning handle —56, thus the wheel dresser element —61, is moved 85 across one of the angular faces —2, of the grinder wheel, thus dressing the wheel to the angle determined by setting of the mechanism relative to scale —49. To dress the opposite face —a, the mechanism is moved 90 a half turn by means of handle —41, as best illustrated in Fig. 4, and the operation of the dresser tool is repeated. Upon turning the mechanism a quarter turn dresser element —60, will be brought into the plane of the 95 grinder wheel, and is then moved into engagement therewith by operating handle —56, to dress the central face —b, between the angular faces 2—2 of the grinder wheel. 100
- As the grinder wheel is reduced by dressing of the wheel, the dresser mechanism as a whole is moved downwardly to a like extent by means of the feed screw handle —20, the adjustment reading being taken 105 on the graduated dial —21. For the convenience of the operator and to insure against error both graduated dials —21, and —29 are made adjustable by means of set screws —21^a and 29^a. Thus in setting the mechanism for grinding the first gear of a given specification, both dials —21 and —29 are set at the zero reading and are thereafter adjusted to the same extent for each wheel dressing operation. By this arrangement the periphery of the grinder wheel is kept at the same distance vertically 110 from the center of the work spindle —62, and all the gears ground will be to the same specification. At intervals the dresser elements —60, and —61, will require adjustment of the mounting heads —60^a and 61^a, to present a new cutting edge to the grinder wheel to compensate for wear of the dresser elements. 115
- In grinding gears on a machine of the character herein illustrated, the dressed edge of the grinder wheel passes through mesh with the gears being ground in the same relation as a master rack tooth with a master gear, thus the edge of the grinder 120
- 125
- 130

- wheel is shaped to give it the same pressure angle, in its relation with the gear teeth, as a master rack tooth would have in the same relation. Thus the matter of angular adjustment of the grinder wheel dresser, as well as the construction and adjustments of the mechanism throughout are matters of first importance from the viewpoint of accuracy. To this end all the sliding bearing surfaces of parts —51, 52, 53, and —57 are hardened, ground and lapped to effect the highest degree of accuracy in the adjustments of the dresser member —53, the accuracy of the construction being maintained indefinitely by the long bearing surfaces which act to minimize wear of the parts.
- Accuracy of construction and provision to minimize wear and to compensate for wear, thus providing for quality and quantity production of ground gears are structural features throughout the mechanism as herein shown and described.
- Having described my invention, I claim:
- 25 1. A grinder wheel dresser including in combination with a member adapted to be moved relative to the grinder wheel and having a bearing aperture, a member supported to rotate in said aperture, a member supported by said second member and adapted to be adjusted angularly thereon, and a dresser tool mounted on the last named member and adapted to be moved into engagement with the grinder wheel.
  - 30 2. A grinding wheel dresser including in combination with a member adapted to be moved relative to the grinder wheel and comprising a laterally extended base having a bearing aperture, a member supported to rotate in said aperture, a member supported by said second member and adapted to be adjusted angularly thereon, and a dresser tool mounted on the last named member and adapted to be moved into engagement with the grinder wheel.
  - 35 3. A grinder wheel dresser including in combination with a member adapted to be moved in a vertical plane relative to the grinder wheel and comprising a base extended laterally in a horizontal plane and having a bearing aperture, a member supported to rotate in said aperture, a member supported by said second member and adapted to be adjusted angularly thereon, and a dresser tool mounted on the last named member and adapted to be moved into engagement with the grinder wheel.
  - 40 4. A grinder wheel dresser including in combination with a member having axial movement and comprising a part having a bearing aperture disposed at an angle to the axis of said member, graduated means to indicate the extent of said movement, a member supported to rotate in said aperture, a member supported by said second member and adapted to be adjusted angularly thereon, and a dresser tool mounted on the last named member and adapted to be moved into engagement with the grinder wheel.
  - 45 5. A grinder wheel dresser including in combination with a member adapted to be moved relative to the grinder wheel and having a bearing aperture, a member supported to be rotated in said bearing aperture to a plurality of predetermined positions, a member supported by said second member and adapted to be adjusted angularly thereon, and a dresser tool mounted on the last named member and adapted to be moved whereby to bring said tool into engagement with different working surfaces of the grinder wheel.
  - 50 6. A grinder wheel dresser including in combination with a member adapted to be moved relative to the grinder wheel and having a bearing aperture, a member supported to be rotated in said bearing aperture to a plurality of predetermined positions, means to adjust said rotatable member relative to said bearing and means to retain said member in one of said predetermined positions, a member supported by said second member and adapted to be adjusted angularly thereon, whereby to bring said tool into engagement with different working surfaces of the grinding wheel.
  - 55 7. A grinder wheel dresser including in combination with a member adapted to be moved relative to the grinder wheel and having a bearing aperture, a member supported to be rotated in said bearing aperture to a plurality of predetermined positions, means to retain said member in one of said positions comprising a part having a notch movable with the rotatable member and a pawl pivoted on said first named member and adapted to engage said notch, a member supported by said second member and adapted to be adjusted angularly thereon, whereby to bring said tool into engagement with different working surfaces of the grinder wheel.
  - 60 8. A grinder wheel dresser including in combination with a member adapted to be moved relative to the grinder wheel and having a bearing aperture, a member supported to be rotated in said bearing aperture, means carried by the rotatable member to adjust the same relative to the bearing comprising a supporting flange for said member on one side of the bearing and an adjusting ring and a lock ring on the opposite side of the bearing, a member supported by said second member and adapted to be adjusted angularly thereon, and a dresser tool mounted on the last named member and adapted to be moved into engagement with the grinder wheel.
  - 65 9. A grinder wheel dresser including in combination with a member adapted to be

10 moved relative to the grinder wheel and having a bearing aperture, a member rotatably supported in said bearing aperture and apertured in the axial plane thereof, a member supported by said second member, within the aperture thereof and adapted to be adjusted angularly relative to the supporting member, and a dresser tool mounted on the last named member and adapted to be moved into engagement with the grinder wheel.

10. A grinder wheel dresser including in combination with a member adapted to be moved relative to the grinder wheel and having a bearing aperture, a member supported on said second member within the aperture thereof and adapted to receive graduated angular adjustments relative thereto, and a dressing tool mounted on the last named member and adapted to be moved relative thereto, whereby to move said tool in variable angular relations into engagement with the grinder wheel.

11. A grinder wheel dresser including in combination with a member adapted to be moved relative to the grinder wheel and having a bearing aperture, a member rotatably supported in said bearing aperture, a member supported on said second member and adapted to receive graduated angular adjustments relative thereto, and a dressing tool mounted on the last named member and adapted to be moved relative thereto, whereby to move said tool in variable angular relations into engagement with the grinder wheel.

12. A grinder wheel dresser including in combination with a member adapted to be moved relative to the grinder wheel and having a bearing aperture, a member rotatably supported in said bearing aperture, a member rotatably supported on said second member and adapted to receive graduated angular adjustments relative thereto, and a dressing tool mounted on the last named member and adapted to be moved relative thereto, whereby to move said tool in variable angular relations into engagement with the grinder wheel.

13. A grinder wheel dresser including in combination with a member adapted to be moved relative to the grinder wheel and having a bearing aperture, a member rotatably supported in said bearing aperture, a member rotatably supported by dovetailed connections on said second member and adapted to receive graduated angular adjustments relative thereto, and a dressing tool mounted on the last named member and adapted to be moved relative thereto, whereby to move said tool in variable angular relations into engagement with the grinder wheel.

14. A grinder wheel dresser including in combination with a member adapted to be

10 moved relative to the grinder wheel and having a bearing aperture, a member rotatably supported in said bearing aperture, a member rotatably supported on said second member by means of a plurality of dovetailed connections arranged to a common center and adapted to receive variable angular adjustments, and a dressing tool mounted on the last named member and adapted to be moved relative thereto, whereby to move said tool in variable angular relations into engagement with the grinder wheel.

15. A grinder wheel dresser including in combination with a member adapted to be moved relative to the grinder wheel and having a bearing aperture, a tool supporting member mounted on said second named member comprising a channelled housing having a head portion, a feed screw supported in said head portion and means for actuating the same, a dresser tool connected to the feed screw and adapted upon operation of the same to be moved slidably in said channelled housing into engagement with the grinder wheel.

16. A grinder wheel dresser including in combination with a member adapted to be moved relative to the grinder wheel and having a bearing aperture, a tool supporting member mounted on said second named member comprising a channelled housing having a head portion, a threaded sleeve and means for operating the same rotatably in said head portion a feed screw adapted to be operated in said sleeve and a dresser tool connected to the feed screw and adapted to be moved slidably thereby in said channelled housing into engagement with the grinder wheel.

17. A grinder wheel dresser including in combination with, a member supported at right angles to the axis of the grinder wheel and adapted to be rotated from one side to the other of the plane of rotation of said wheel, a member supported by said rotatable member and adapted to be adjusted angularly in the axial plane thereof, and a dresser tool supported on said adjustable member and adapted to be moved at variable angles into engagement with the grinder wheel.

18. A grinder wheel dresser including in combination with a reciprocating ram having a grinder wheel mounted thereon, a member supporting the grinder wheel and adapted to be raised and lowered in a vertical plane, a member supported on said first named member and adapted to be adjusted vertically relative to the grinder wheel, a member supported on said last named member and adapted to be rotated at right angles to the plane of rotation of the grinder wheel, a member mounted at an angle on said rotatable member, and a

dresser tool operable in said angular member into engagement with the grinder wheel.

19. A grinder wheel dresser including in combination with a ram having a grinder wheel mounted thereon, a member supported on the ram and adapted to be moved in the plane of rotation of the grinder wheel, a member supported on said last named member and adapted to be rotated at right angles to the plane of rotation of the grinder wheel, a member mounted on an angle on said rotatable member, and a dresser tool operable in said angular member into engagement with the grinder wheel.
- 15 20. A grinder wheel dresser including in combination with a ram having a grinder wheel mounted thereon, a member supported on the ram and adapted to be rotated at right angles to the plane of rotation of the

grinder wheel, a member mounted and adjustable angularly on said rotatable member, and a dresser tool operable in said angular member into engagement with the grinder wheel.

21. A grinder wheel adapted to be adjusted vertically relative to the work spindle of a gear grinder, a wheel dresser adapted to be adjusted vertically relative to the grinder wheel, separate graduated means to indicate the extent of each of said adjustments and means to adjust said graduated means relatively one to the other whereby to effect coordinated readings thereof in grinding gears in quantities to a given specification.

In testimony whereof, I affix my signature.

ORLANDO GARRISON.
